Specification for Design.

Patented Mar. 27, 1917.

Application filed February 14, 1917. Serial No. 148,636. Term of patent 7 years.

To all whom it may concern:

Be it known that I, WALTER R. KAHNS, a citizen of the United States, residing at Chicago, in the county of Cook and State of Illinois, have invented a new, original, and ornamental Design for Hanger-Hooks for Light-Reflecting Bowls, of which the following is a specification, reference being had to the accompanying drawing, forming part thereof, in which—

Figure 1, is a side elevation of a hanger hook for light reflecting bowls, showing my new design, and

Fig. 2, is a rear elevation of the same.

I claim:

The ornamental design for a hanger hook for light reflecting bowls, as shown.

WALTER R. KAHNS.
